United States Patent Office.

JAMES NICKLIN, OF CLEVELAND, OHIO.

Letters Patent No. 98,094, dated December 21, 1869.

IMPROVED CURTAIN AND SHAWL-STRETCHER.

The Schedule referred to in these Letters Patent and making part of the same.

To all whom it may concern:

Be it known that I, JAMES NICKLIN, of Cleveland, in the county of Cuyahoga, and State of Ohio, have invented certain new and useful Improvements in a Curtain and Shawl-Stretcher; and I do hereby declare that the following is a full and complete description of the same, reference being had to the accompanying drawings, making part of this specification, in which—

Figure 1 is an edge view of the stretcher.

Figure 2, a side view of the same.

Like letters of reference refer to like parts in the different views.

The purpose of this invention is for stretching shawls, curtains, and other like delicate fabrics after being washed, thereby preventing them from shrinking, and becoming warped and wrinkled in the process of drying.

This stretcher consists of a rectangular frame, as shown in fig. 2, in which it will be seen that in each side, A, is cut a lengthened slot, B.

In said slot is inserted, at each corner or point of conjunction, a bolt, C, fig. 1, provided with a finger-nut, D, whereby the several sections of the frame are secured to each other, and which admits of the extension and contraction of the size of the frame, so as to adapt it to the nature and size of the article to be operated upon.

Along the inner edge of each side or section A, is cut a rabbet, E, in which is arranged a series of sharp-pointed pins, *a*, also indicated by the dotted lines *b*, fig. 1, the purpose of which will hereinafter be shown.

It is well known that shawls, curtains, and other articles of a delicate nature, in the process of drying

after being washed, are liable to shrink and become wrinkled and more or less warped out of shape, and, in consequence of the frail and delicate nature of the material, cannot be ironed out, and thereby freed from such wrinkles and unevenness without serious injury to the articles.

To avoid this injury to the material, and to retain the shape, size, and smoothness of the fabric, is the purpose of this frame, and which is used in the following manner, viz:

The shawl or other article, on being washed, is then secured to the frame, hooking the extreme edges thereof on the pins *a*. This having been done, the frame or sides of the frame are then forced outward, thereby stretching the article thereon, which is held thus expanded by clamping the frame together by the bolt and nut C D. In this condition it is allowed to dry on the frame, and which, when dry, will be found to be smooth, unshrunken, and free of any distortion of the shape or pattern, and requires no ironing or pressing, as a finishing for the work of cleaning.

It will be obvious that the adjustable character of the frame will allow of its being adapted to various sizes of goods, so that large or small articles can be stretched and dried thereon.

What I claim as my improvement, and desire to secure by Letters Patent, is—

The adjustable sides A, when constructed with slots B, rabbet E, and pins *a*, and screwed to each other in the manner substantially as described, and for the purpose set forth.

JAMES NICKLIN.
